ELECTROPLATING FIXTURE

Morton Kaufman, Brooklyn, N. Y., assignor to
 Wright Aeronautical Corporation, a corpora-
 tion of New York

Application July 16, 1943, Serial No. 495,004

8 Claims. (Cl. 204—286)

1

This invention relates to apparatus for electroplating and is particularly directed to an electroplating fixture adapted to facilitate the electroplating of a limited portion of an article.

In aircraft engines it is common practice to chromium plate the crankshaft bearing surfaces. In order to prepare the crankshaft for the electroplating operation it has been the general practice to cover that portion of the surface of the crankshaft, which is not to be plated, with alternate coats of paint and tinfoil. Because of the irregular nature of the crankshaft surface this procedure takes considerable time. It is an object of this invention to provide an electroplating fixture which makes it unnecessary to so cover that portion of the surface of the crankshaft or other object which is not to be plated. It is a further object of this invention to provide an electroplating fixture which may be readily attached to the object to be plated and which fixture, when in position on the object, effectively shields all of the surface of the object from the anode except that portion of the surface to be plated. That is, the invention comprises an electroplating fixture in which the anode is shielded and so disposed that only the surface to be plated is exposed to current flow from the anode.

Other objects of this invention will become apparent from reading the annexed detailed description in connection with the drawing in which:

Figs. 1 and 2 are perspective views of the front and rear sections, respectively, of a conventional aircraft engine crankshaft;

Fig. 3 is a vertical sectional view illustrating an electroplating fixture in position for plating the rear external bearing of the crankshaft;

Fig. 4 is a vertical view partly in section of a modified fixture for plating the front crankshaft section bearing;

Fig. 5 is a perspective view of the anode used in the fixture of Fig. 3;

Fig. 6 is a section on line 6—6 of Fig. 5; and

Fig. 7 is a vertical sectional view through an electroplating fixture in position for plating the internal bearing of the rear crankshaft section.

Referring to Figs. 1 and 2, these figures illustrate a conventional two-part single throw crankshaft of an aircraft engine. The rear crankshaft portion 10 is provided with a clamp bolt construction 12 which is adapted to clamp about the crankpin 14 integral with the front crankshaft section 16. The rear crankshaft section is provided with an outer bearing surface 18 or band-like area 18 and an inner bearing

surface 20, both of which are to be plated with chromium. The remainder of the surface of the rear crankshaft section 10 is to remain unplated and, in accordance with the present practice, this portion of the crankshaft surface is covered with alternate layers of paint and tinfoil. Similarly, the front crankshaft section has the front bearing surface or band-like area 22 which is to be plated while the remainder of the surface of this front crankshaft section is to remain unplated. As is readily apparent from the irregular nature of the crankshaft, as illustrated in Figs. 1 and 2, the operation of covering that portion of the crankshaft surface which is not to be plated, with layers of paint and tinfoil is quite tedious and time consuming. In fact, in practice it has been found that the preparation of the front crankshaft section for electroplating consumes approximately 195 minutes while with the use of the fixture hereinafter described this time is cut to approximately 5 minutes. Similar proportionate savings in time have been obtained from use of the electroplating fixture herein disclosed with the rear crankshaft section. In addition, the saving of tin resulting from the use of this fixture is also an important factor particularly because of the present day importance of tin.

Now referring to Fig. 3, an electroplating tank 24 is provided with positive and negative electric terminal rods 26 and 28 and this tank is provided with an electrolytic solution of chromic acid. The object to be plated is suspended from a beam 30 of wood or other suitable insulating material and this beam is supported across the terminal rods 26 and 28. In order to plate the outer bearing surface 18 of the rear crankshaft section 10 a fixture 31 is supported from the beam 30 by a bracket 32. The fixture 31 comprises a cathode steel sleeve 34 supported from the bracket 32 and threaded to the external threads 36 on the rear crankshaft section 10. The exposed surface of the cathode sleeve preferably is covered with any suitable insulating material 35; for example, a plastic insulating tape known as "Rap-Rax" is quite satisfactory. The bracket 32 is secured to the beam 30 over a copper strip 33 which is secured to the under side of the beam and runs to one end of this beam. Thus, when the beam 30 is disposed across the terminal rods 26 and 28 the negative terminal 28 is connected to the crankshaft section 10 through the copper strip 33, bracket 32, and cathode sleeve 34. Cemented to the steel sleeve 34 is an insulating collar 38 which may be made of any suitable insulating or plastic

material such as "unichrome" which is not affected by the particular electrolyte used.

Slidably mounted on the insulating collar 38 is a steel sleeve 40 to which upwardly extending fingers 42 of the anode 44 are secured by soldering or in any other suitable manner. These fingers 42 are covered with a suitable insulating material 43, for example, with the aforementioned "Rap-Rax" tape, and a plurality of flexible wire leads 45 are soldered or otherwise secured to these fingers and to the steel sleeve 40. The other end of the flexible wires 45 are connected together to the underside of the beam 30 and in contact with a second copper strip 47 which extends to that end of the beam disposed over the electric terminal rod 26. The anode 44 is a cylindrical member preferably made of lead which is adapted to be concentrically disposed about the bearing surface 18 and in spaced relation thereto. In practice it has been found necessary to provide an in-turned flange 43 at the bottom of the anode in order to obtain an even plate. Also, the anode 44 is tightly fitted within the cylindrical shield 46 having a tapered in-turned flange 48. This shield 46 is made of suitable insulating material and may also be made of the above-mentioned plastic known as "unichrome." The body of the shield 46 covers the outer surface of the anode 44 while the flange 48 extends around under the anode and up to the bearing surface to be plated to provide a stop-off for the plating operation. The structure of the anode 44 and shield 46 is best seen in Figures 5 and 6. With this construction, the in-turned flange 48 on the shield 46 extends inwardly from the lower edge of the anode 44 and terminates adjacent to the corresponding or lower edge of the annular area 18 to be plated.

In an electroplating process the current flow through the electrolyte is substantially confined to the solution directly between the anode and cathode, the body to be plated forming the cathode. That is, the lines of electric current flow through the electrolyte are substantially straight lines between the anode and the surface to be plated. Therefore, with the shield 46 fitted around the outer and bottom surfaces of the anode the current flow through the electrolyte from the anode is limited to the radial space between the anode and cathode. Accordingly, the presence of the shield 46 prevents radially outward and downward current flow through the electrolyte thereby making it unnecessary to cover any portion of the surface of the crankshaft section 10 except that immediately to the rear or above the surface 18 to be plated. The cathode sleeve 34 is threaded down on the crankshaft threads 35 to the bearing surface 18, thereby covering and shielding the surface of the crankshaft immediately above the surface 18 to be plated as viewed in Fig. 3. The anode 44 and its shield 46 are secured together and to the slidably mounted sleeve 40; therefore, the flange 48 of the shield 46 may be tightly placed against the crankshaft adjacent to the lower edge of the surface 18.

Bearing surface 22 of the front crankshaft section 16 may be plated with the aid of a fixture similar to that just described and this fixture may be secured to the threads 50 on this crankshaft section. However, in addition, a sleeve must be placed over the crankshaft to cover that portion of the crankshaft immediately in front of the bearing surface 22. No such sleeve is necessary in plating the bearing surface 18 of the rear crankshaft section because of the location of the threads 35 immediately adjacent the bearing sur-

face 18 whereby the cathode sleeve 34 itself effectively shields that portion of the rear crankshaft section immediately above the bearing surface 18.

In Fig. 4 a modified fixture 52 is illustrated for chromium plating the bearing surface 22 of the front crankshaft section 16. In this fixture the lead anode 54 and insulating sleeve 56 are similar to that illustrated in Fig. 3 and the anode is supported by fingers 58 secured to the insulating sleeve 60. This insulating sleeve, instead of being mounted on a cathode sleeve as in Fig. 3 is supported directly on the crankshaft over the splines 62. In assembly, the fixture is slipped down over the shaft until the inturned flange 57 of the sleeve 56 abuts against the boss 64 adjacent one end of the bearing surface 22, and the sleeve 60 is of such length that it terminates just in front of the bearing surface 22. The fingers 58 like the fingers 42 are covered with suitable insulating material. The sleeves 56 and 60 thereby are operative to completely shield all of the surface of the crankshaft except the bearing surface 22, as in previous modification. Instead of an insulating sleeve 60, it is obvious that a metallic sleeve may be substituted therefor with the fingers 58 suitably insulated and supported therefrom.

The crankshaft section and its fixture are supported by a beam 66 mounted upon electric terminal rods 68 and 70, as in Fig. 3. A copper strip 72 is secured under one end of this beam for contact with the positive terminal rod 68 and a plurality of electric leads 74 are secured at one end to the beam 66 in contact with this copper strip and are soldered at their other ends to the anode fingers 58. The beam 66 is provided with a bore 76 for the reception of the front end of the crankshaft. The crankshaft and its fixture are supported from the beam by a rod 78 secured to a supporting plate 80 mounted upon the upper side of the beam. This rod is provided with a pair of centering collars 82 having a diameter corresponding to the internal diameter of the crankshaft. These centering collars are each secured to the supporting rod by a pair of segmental shaped washers 84. The lower collar 82 is provided with a radial hole 86 and is mounted upon the rod 78 so as to line up with a drilling 88 found in the crankshaft. With this construction the rod 78 and its centering collars 82 may be inserted within the crankshaft and a pin 90 placed through the aligned holes 86 and 88 to support the crankshaft from the beam 66. A copper strip 92 is secured to the beam and extends from engagement at one end with the negative terminal rod 70 to engagement with the crankshaft and supporting rod 78. The washers 84 are segmental shaped to permit circulation of air through the crankshaft holes in order to permit escape of any chromic acid vapors therein.

In order to plate an internal bearing surface, for example, the internal bearing surface 20 on the rear crankshaft section 10, a fixture 94 of somewhat different construction is required as illustrated in Fig. 7. This fixture 94 consists of a cathode sleeve 96 threadedly secured to the crankshaft threads 36. A cross strap 98 is secured across the top of the sleeve 96 and a bracket 99 is secured to the sleeve and to a beam 100 for supporting the fixture and attached crankshaft section. The supporting beam 100 is made of wood or other suitable material and is mounted across the tank 102 upon the positive and negative terminal rods 104 and 106. A copper strip 108 secured to the under side of the beam 100 connects the negative terminal rod

106 with the crankshaft section 10 through the bracket 98 and the cathode sleeve 96. The anode 110 is preferably made of lead and is supported by a steel rod 112 secured to the beam 100 and to the cross strap 98 to help support the fixture and to concentrically dispose the anode within the internal bearing 20. A copper strip 114 is disposed along the under side of the beam 100 and electrically connects the positive terminal 104 with the anode 110 through the steel rod 112. Suitable insulating washers are disposed between the rod 112 and the cross strap 98 to insulate these members from each other.

Before the fixture 94 is secured to the rear crankshaft section 10 a suitable stop-off collar 116 is disposed about the upper portion of the bore through the crankshaft section 10. This stop-off collar 116 is made of suitable insulating material and is provided with a steel backing 118. Also, this stop-off collar is supported on the shoulder 120 formed at the upper end of the bearing surface 20 and because of the generally conical shape of this shoulder, the stop-off collar is self centering. The manner in which the stop-off collar 116 is supported obviously depends on the structure of the crankshaft adjacent the surface to be plated.

When the fixture 94 is secured to the beam 100 the anode 110 is concentrically disposed within the bearing 20. Accordingly, the current flow from the anode through the electrolyte will be radially outward to the bearing surface 20. The lines of flow of the current from the anode will extend slightly around the corner 122 but this is not serious since this portion of the crankshaft is subsequently polished.

From the above description it is apparent that the fixtures 31 and 52 both provide a convenient apparatus for electroplating a portion of an external surface of a body and which apparatus eliminates the necessity of providing a protective coating over the remainder of the surface of the body. The fixtures 31 and 52 both are particularly suited for plating external bearing surfaces or other similarly shaped surfaces of a body. The fixture 94 is particularly suited for plating an internal bearing surface or other similarly shaped surfaces, and this fixture also eliminates the necessity of providing the protective coating over the remainder of the surface of the body.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. An electroplating fixture for plating a circumscribing band-like area on the surface of an object disposed in a suitable electrolyte, said fixture comprising tubular shield means adapted to embrace said object adjacent to one edge of said band-like area, a tubular anode member supported from said shield means and arranged to be disposed in said electrolyte so as to surround said band-like area in spaced relation thereto, shield means embracing the surface of said anode member remote from said band-like area, said shield means having a portion extending inwardly from one edge of said anode member and terminating adjacent to the other edge of said band-like area.

2. An electroplating fixture for plating a circumscribing band-like area on the surface of an object disposed in a suitable electrolyte, said fixture comprising tubular shield means adapted to embrace said object adjacent to one edge of said band-like area, a tubular anode member having a plurality of finger-like extensions for supporting said member from said shield means and arranged to be disposed in said electrolyte so as to surround said band-like area in spaced relation thereto, shield means embracing the surface of said anode member remote from said band-like area, said shield means having a portion extending inwardly from one edge of said anode member and terminating adjacent to the other edge of said band-like area.

3. An electroplating fixture for plating a circumscribing band-like area on the surface of an object disposed in a suitable electrolyte, said fixture comprising a first tubular shield means adapted to snugly embrace said object, a tubular anode member supported from said shield means and adapted to be disposed in said electrolyte about and in spaced relation to said band-like area, and a second tubular shield means embracing the surface of said anode member remote from said band-like area and having an inwardly extending portion, said fixture when in position on said object having an edge of said first shield means disposed adjacent to one edge of said band-like area and having the inwardly extending portion of said second shield means terminating adjacent to the other edge of said band-like area.

4. Apparatus for electroplating a circumscribing band-like area about an object disposed in a suitable electrolyte, said apparatus comprising a tubular anode member to be disposed in said electrolyte about said band-like area in spaced relation thereto, and shield means disposed about the surface of said anode member remote from said band-like area, said shield means having a portion extending inwardly from one edge of said anode member and terminating adjacent an edge of said band-like area.

5. Apparatus for electroplating a circumscribing band-like area about an object disposed in a suitable electrolyte, said apparatus comprising a tubular anode member to be disposed in said electrolyte about said band-like area in spaced relation thereto, said anode member having a portion extending inwardly from its lower edge toward, but terminating short of, the lower edge of said band-like area as said object is positioned in said electrolyte, tubular shield means embracing said object above said band-like area, said shield means terminating adjacent the upper edge of said band-like area, and second shield means embracing the surface of said anode member remote from said band-like area, said second shield means having a portion extending inwardly from the lower edge of said anode member below the inwardly extending portion of said anode member and terminating adjacent the lower edge of said band-like area.

6. Apparatus for electroplating a circumscribing band-like area about an object disposed in a suitable electrolyte, said apparatus comprising a tubular anode member to be disposed in said electrolyte about said band-like area in spaced relation thereto, tubular shield means embracing said object above said band-like area as said object is positioned in said electrolyte, said shield means terminating adjacent the upper edge of said band-like area, second shield means em-

bracing the surface of said anode member remote from said band-like area, said second shield means having a portion extending inwardly from the lower edge of said anode member and terminating adjacent to the lower edge of said band-like area, and means for supporting said anode member and second shield means from said first-mentioned shield means.

7. Apparatus for electroplating a circumscribing band-like area about an object disposed in a suitable electrolyte, said apparatus comprising a tubular anode member to be disposed in said electrolyte about said band-like area in spaced relation thereto, tubular shield means embracing said object above said band-like area as said object is positioned in said electrolyte, said shield means terminating adjacent the upper edge of said band-like area, and second shield means embracing the surface of said anode member remote from said band-like area, said second shield means having a portion extending inwardly from the lower edge of said anode member and terminating adjacent to the lower edge of said band-like area.

8. An electroplating fixture for plating a circumscribing band-like area on the surface of an object, said fixture comprising a first tubular member secured about said object adjacent to one edge of said band-like area to comprise a shield for said object, a tubular anode member slidably supported from said first tubular mem-

ber and adapted to surround said band-like area in spaced relation thereto, and a shield member embracing the surface of said anode member remote from said band-like area, said shield member having a flange extending inwardly from an edge of said anode member and terminating adjacent to the other edge of said band-like area.
